US00D968686S

(12) **United States Design Patent** (10) Patent No.: **US D968,686 S**
(45) Date of Patent: **** Nov. 1, 2022**

(54) **ELECTRONIC CIGARETTE**

- (71) Applicant: **Altria Client Services LLC**,
Richmond, VA (US)
(72) Inventor: **Mitchell Stone**, Staffordshire (GB)
(73) Assignee: **Altria Client Services LLC**,
Richmond, VA (US)
(**) Term: **15 Years**
(21) Appl. No.: **29/756,812**
(22) Filed: **Oct. 30, 2020**

Related U.S. Application Data

- (62) Division of application No. 29/710,972, filed on Oct. 28, 2019, now Pat. No. Des. 901,069, which is a division of application No. 29/662,845, filed on Sep. 10, 2018, now Pat. No. Des. 878,671, which is a division of application No. 29/592,191, filed on Jan. 27, 2017, now Pat. No. Des. 829,369.

CLAIM

The ornamental design for an electronic cigarette, as shown and described.

DESCRIPTION

FIG. 1 is a perspective view of an electronic cigarette; FIG. 2 is a front view of the electronic cigarette; FIG. 3 is a rear view of the electronic cigarette; FIG. 4 is a left side view of the electronic cigarette; FIG. 5 is a right side view of the electronic cigarette; FIG. 6 is a top view of the electronic cigarette; and, FIG. 7 is a bottom view of the electronic cigarette. The evenly spaced broken lines in the drawings depict portions of the electronic cigarette that form no part of the claimed design; the dash-dot-dash lines represent boundary lines for the claimed design.

U.S. Office Action dated Jan. 5, 2018 in related U.S. Appl. No. 29/592,211.
U.S. Office Action dated May 14, 2019, in related U.S. Appl. No. 29/662,847.
U.S. Office Action dated May 14, 2019, in related U.S. Appl. No. 29/662,843.
U.S. Office Action dated May 23, 2019 in corresponding U.S. Appl. No. 29/662,871.
U.S. Office Action dated May 23, 2019 in corresponding U.S. Appl. No. 29/662,859.
U.S. Office Action dated May 23, 2019 in corresponding U.S. Appl. No. 29/662,845.
U.S. Office Action dated May 23, 2019 in corresponding U.S. Appl. No. 29/662,880.
U.S. Office Action dated May 23, 2019 in corresponding U.S. Appl. No. 29/662,888.
Notice of Allowance dated Nov. 19, 2019, issued in corresponding U.S. Appl. No. 29/662,845.
U.S. Office Action dated May 22, 2020 in corresponding U.S. Appl. No. 29/710,932.
Notice of Allowance dated Jun. 4, 2020, issued in corresponding U.S. Appl. No. 29/710,943.

Notice of Allowance dated Jun. 4, 2020, issued in corresponding U.S. Appl. No. 29/710,946.
Notice of Allowance dated Jun. 4, 2020, issued in corresponding U.S. Appl. No. 29/710,936.
Notice of Allowance dated Jun. 4, 2020, issued in corresponding U.S. Appl. No. 29/710,972.
U.S. Office Action dated Jun. 5, 2020 in corresponding U.S. Appl. No. 29/710,951.
U.S. Office Action dated Jun. 5, 2020 in corresponding U.S. Appl. No. 29/710,957.
Notice of Allowance dated Jul. 6, 2020, issued in corresponding U.S. Appl. No. 29/710,943.
Notice of Allowance dated Jul. 2, 2020, issued in corresponding U.S. Appl. No. 29/710,946.
Notice of Allowance dated Jul. 6, 2020, issued in corresponding U.S. Appl. No. 29/710,936.
Notice of Allowance dated Jul. 2, 2020, issued in corresponding U.S. Appl. No. 29/710,972.
Notice of Allowance dated Aug. 26, 2020, issued in corresponding U.S. Appl. No. 29/710,932.
Notice of Allowance dated Sep. 11, 2020, issued in corresponding U.S. Appl. No. 29/710,957.
Notice of Allowance dated Sep. 16, 2020, issued in corresponding U.S. Appl. No. 29/710,951.
Office Action dated Nov. 12, 2021, issued in corresponding U.S. Appl. No. 29/756,808.
Office Action dated Nov. 12, 2021, issued in corresponding U.S. Appl. No. 29/756,815.
Office Action dated Nov. 12, 2021, issued in corresponding U.S. Appl. No. 29/756,805.
Notice of Allowance dated Mar. 2, 2022, issued in corresponding U.S. Appl. No. 29/756,808.
Notice of Allowance dated Mar. 4, 2022, issued in corresponding U.S. Appl. No. 29/756,805.
Notice of Allowance dated Feb. 24, 2022, issued in corresponding U.S. Appl. No. 29/756,815.
